United States Patent

Des. 240,168
Patented June 1, 1976

240,168

COMBINATION CARD AND VIEWER

James C. Brettman, 2770 NE. 6th St., and Mary Lynne Lauson, 777 S. Federal Highway, both of Pompano Beach, Fla. 33062

Filed Jan. 28, 1974, Ser. No. 436,991

Term of patent 14 years

Int. Cl. D20—03

U.S. Cl. D96—12 F

Fig. 1.

Fig. 2.

Fig. 3.

FIG. 1 is an isometric view of a combination card and viewer showing our new design;

FIG. 2 is a side view of the combination card and viewer; and

FIG. 3 is an open flat plan view of the combination card and viewer.

I claim:

The ornamental design for a combination card and viewer, substantially as shown.
